Primary Examiner — Sheryl Lane*Assistant Examiner* — Mark T Philippi(74) *Attorney, Agent, or Firm* — Endurance Law Group PLC(57) **CLAIM**

We claim the ornamental design for a coolant radiator core, as shown and described.

DESCRIPTION

FIG. 1 is front perspective view of a coolant radiator core according to the present invention;

FIG. 2 is rear perspective view of the coolant radiator core;

FIG. 3 is a front view of the coolant radiator core;

FIG. 4 is a left side view of the coolant radiator core;

FIG. 5 is a right side view of the coolant radiator core;

FIG. 6 is a rear view of the coolant radiator core;

FIG. 7 is a top view of the coolant radiator core; and,

FIG. 8 is a bottom view of the coolant radiator core.

The broken lines represent the exemplary end tanks, cooling fins/tubes, fill neck and hose fittings and form no part of the claimed design.
